UNITED STATES PATENT OFFICE

PAUL RODIER, OF PARIS, FRANCE, ASSIGNOR TO RODIER, OF PARIS, FRANCE, A LIMITED JOINT-STOCK COMPANY OF FRANCE

PROCESS FOR THE MANUFACTURE OF CHENILLE FRINGES OR OTHER SIMILAR ORNAMENTS AND PRODUCTS

Application filed February 10, 1928, Serial No. 253,357, and in France February 18, 1927.

The present invention relates to the manufacture of fringes or ornaments by the aid of chenille, old in itself, and consisting of a core of a suitable material and a covering of threads of silk or wool, imparting to the chenille the appearance of a satin cord.

The object of the invention is to transform known chenilles of this kind into a product having, at a distance, the appearance of feathers. This object is attained by means of the method hereinafter claimed and described with reference to the accompanying drawing, in which Figs. 1 to 4 illustrate the several stages in the production of known types of chenille.

Fig. 5 is a front view of the provisional fabric.

Fig. 6 shows a portion of this provisional fabric on a larger scale.

Fig. 7 is a section of the provisional fabric on the line 7,7, of Fig. 5.

Fig. 8 is a view of the chenille after stripping off the provisional fabric.

Fig. 9 is a view of a chenille fringe made in accordance with the invention.

Figure 10 is a plan view of a section of provisional fabric which forms an intermediate step in the manufacture of fanciful effects in fringes according to this invention.

A provisional fabric is first woven with two selvedges 3¹ 3² and consists of chenilles 1, 2 forming weft threads and an auxiliary thread of any kind forming the warp.

These chenilles are obtained by securing to the cotton core 1 (Figs. 1 and 2) silk threads 2 or the like and passing this assembly through a tube, producing a chenille consisting of a cotton core and a silk facing.

Figs. 6 and 7 show the formation of the provisional fabric in detail. In particular it will be seen that the warp threads 4 become embedded in the silk coating 2 of the chenille and produce scallops in it (Fig. 7).

The provisional fabric is then dyed by known methods. The effect of dyeing is to increase the aforesaid effects, viz: the penetration of the auxiliary thread 4 into the silk coating 2 of the chenille.

The provisional fabric is then stripped off,

the threads of the auxiliary warp 4 being entirely removed from this fabric and its selvedge 3². Thus a fringe is made (Fig. 9) consisting of chenilles with a covering 2 scalloped here and there as a result of auxiliary warp threads, like the chenille shown in detail in Fig. 8. These fringes look like feathers at a distance.

Numerous alterations can be made in the aforesaid process described, for example.—
In the first place by means of this process very varied ornaments can be made, sashes, flounces for dresses etc., and even simple scalloped chenilles can be made. For this it suffices, in fact to undo the two selvedges 3¹ 3² of the ornament, removing the auxiliary warp thread 4 from the entire provisional fabric and this will completely release the chenille 1, 2 after the action of this warp thread on the covering 2 thereof.

The aforesaid process can also be applied by omitting the operation of dyeing the provisional fabric and by printing the latter instead. Thus chenilles can be made printed with any suitable design.

The chenille coverings 2 may be in one colour or formed, on the other hand, with several threads of different colours.

The provisional fabric illustratively exemplified in Figure 10, is formed by means of chenille 2 and of an auxiliary thread 4; the fabric having two selvedges 10' and 10².

The provisional fabric is divided into alternate squares 15' and 15². In the square 15' each chenille 2 passes alternately under and over an auxiliary thread 4. Consequently, in the square 15² the auxiliary threads 4 present on the outer face of the fabric, a very close and regular network.

In the square 15², on the contrary, the chenille 2 passes alternately over an auxiliary thread 4, then below three or four auxiliary threads 4 and so on indefinitely. Consequently, in the square 15², the auxiliary threads 4 present on the outer face of the fabric a very loose but nevertheless regular network.

Summarizing, while in the square 15' the depressions formed in the chenille 2 are separated from each other a short distance *d*, in

the square 15², on the contrary, the undulations of this chenille 2 are separated from each other a substantial distance D.

The provisional fabric thus obtained is then treated as explained in the case of Figs. 1 to 9, i. e., the provisional fabric is printed and then decorticated by removing the auxiliary thread 4.

In this manner, fringes are obtained which have been irregularly depressed or grooved by the auxiliary threads 4 and consequently present fanciful effects and various designs.

The invention not only comprises the aforesaid processes but also includes the new industrial products, such as fringes, chenilles, and other ornaments made by the improved processes.

In particular the invention concerns a chenille 1, 2, the covering 2 of which is scalloped here and there, the chenille thus having a characteristic appearance.

Claims:

1. As a new article of manufacture, a fringe; trimming or the like consisting of strands of chenille each strand comprising a core and a strand-like facing with the facing strands substantially adhering to the core at intervals and standing away therefrom between the adhering portions whereby the article as a whole presents, at a distance, the appearance of feathers.

2. The herein described method of manufacturing fringes, trimmings, passementerie and the like from chenille, which latter comprises a core and a strand-like facing, which method consists in applying external pressure to the facing at intervals along the length of the chenille to cause the strands of the facing to substantially adhere to the core at the places where the pressure was applied and thereafter removing the pressure, whereby the chenille will have alternate relatively smooth and feather-like areas.

3. The herein described method of manufacturing fringes, trimmings, passementerie and the like from chenille, which latter comprises a core and a strand-like facing, which method consists in weaving together a chenille and an auxiliary thread with sufficient pressure of the latter against the chenille to cause the strands of the facing to substantially adhere to the core at intervals along the length of the core and thereafter removing the auxiliary thread so that the chenille will have alternate relatively smooth and feather-like areas.

In testimony whereof I affix my signature.
PAUL RODIER.
